UNITED STATES PATENT OFFICE

ALFRED E. OSWALD, OF HACKENSACK, NEW JERSEY, ASSIGNOR TO UNDERWOOD ELLIOTT FISHER COMPANY, OF NEW YORK, N. Y., A CORPORATION OF DELAWARE

ELECTRIC MOTOR

Original application filed December 13, 1922, Serial No. 606,575. Divided and this application filed November 24, 1928. Serial No. 150,592. Renewed October 10, 1928.

This invention relates primarily to motors which are alterable for use with either alternating or direct current, and to work in circuits having different frequencies, etc.

5 The invention relates particularly to the construction of an annular field-magnet core for said motor. To facilitate the assembly or removal of pre-wound field-coils, the core consists of separable portions. Each core-
10 portion is laminated and provision is made for uniform laminations or punchings for both cores.

Means for holding the two core-portions together may consist simply of a tight sleeve 15 fitting around the assembled core-portions and pressing them firmly together in a direction substantially normal to the joints to secure a good magnetic bond at said joints. Besides the fact that the abutting surfaces of
20 two core-portions are directly pressed together, that is to say, from diametrically opposite directions, to secure a good magnetic bond, said good bond is further assured because the core is made up of only two portions, that is to say, only two joints need be made, one joint at each pair of abutting legs 25 of the semi-annular core-portions. To further conduce to a good magnetic bond, each U-shaped punching may have a V-point or
30 taper at the end of one extremity or leg, and a V-recess or socket on the other leg. In each core-portion every alternate punching may be reversed, so that, in the assembly, the points of each core-portion alternate with the recesses. The built-up halves of the magnet 35 may then be assembled and form dovetailed joints, the points of each half fitting in the recess of the other half, and the joints overlapping, making an excellent magnetic joint, 40 safeguarding the magnet against ordinary rough usage, preventing relative displacement of the core-portions, and permitting the poles to approach closely to the armature with reduced liability of collision.

45 The use of a core-retaining casing or sleeve surrounding the core and holding its semi-annular portions firmly together through pressure applied substantially from diametrically opposite directions obviates the need
50 for using bolts or similar devices passing

transversely through the laminations to clamp the overlapping portions of laminations of the opposite core-halves together. While the latter method of clamping the core-halves together may secure a good magnetic joint, its application is apt to be unfeasible for some types of motors, as, for example, the motor herein shown, which, on account of its desired compact arrangement, affords little or no room for such transverse 55 fastenings. 60

Another feature of improvement relates to cleft pole-pieces of the field-magnet core, and to provision for placing the field-coils in such relation to the cleft pole-pieces as to balance or take care of armature reaction. This feature has a special benefit where the field-coils are to be connectible in either series, or parallel, or multiple series. 65

This application is a division of my application, Serial No. 606,575, filed December 13, 1922 (now Patent No. 1,713,617, dated May 21, 1929). 70

Other features and advantages will hereinafter appear. 75

In the accompanying drawings,

Figure 1 is a diagrammatic elevation of a motor embodying the present improvements in one form, the frame and certain parts being shown in section. 80

Figure 2 is a sectional elevation of the upper portion of a motor embodying certain of the improvements in another form, with the field coils placed directly upon the pole-pieces, instead of upon the necks of the field 85 magnet as at Figure 1.

In order that the utility and advantages of the invention may be readily understood a brief description of the herein-shown motor will at this point be given and will be followed by a description of the field-magnet core to which the invention particularly relates. It will be understood that the invention is not limited to the particular motor shown but may advantageously be applied to other types of motors. 90

The motor-shaft 40 carrying an armature 41 is journaled in bearings carried by the framework, which includes a barrel, drum or casing 46; said casing having the usual ends 100

(not shown) which may be separately joined thereto.

The commutator 47 co-operates with the usual main brushes 48 to transmit current to the revolving armature coils. The motor is for use on either alternating current or direct current. To minimize sparking at the main brushes 48 when the motor is used on alternating current a pair of auxiliary brushes 48^a is provided to short-circuit the currents which arise from the usual transformer-like action and which cause said sparking. In order that the auxiliary brushes may not cause serious sparking when the motor is used on direct current, the armature coils, short-circuited by said auxiliary brushes as they span adjacent commutator segments, are caused to be in a weak field, so that the current induced in said last-mentioned armature coils and consequently the sparking are minimized. The opposite poles of the field-magnet are therefore divided each by a cleft 58. Thus one pole includes parts 53 and 53^a and the other pole includes parts 54 and 54^a. The armature coils short-circuited by auxiliary brushes 48^a may be caused to pass the clefts 58 at the moment of said short-circuiting and thereby minimize sparking. Field-coils 49-52 are connectible in series, parallel, or series-parallel in respect to each other but, in general, are in shunt relation to the armature. Auxiliary field-coils 66-73 are also connectible in various ways in respect to each other but, in general, are in series relation to the armature and may oppose or assist coils 49-52.

For compacting the motor an annular field core shape is selected. All the field-coils are pre-wound, and the present invention provides for easy assembling or removal of said coils upon or from said annular core, which is built up of laminations which may be held together by rivets 61. To this end, the annulus 55 is made in two parts, joined preferably at what is substantially a plane through the axis of the core, or, in other words, a plane midway between the opposite pole faces. Thus each semi-annular core-portion is substantially U shaped with the aforesaid cleft 58 between extremities or legs 59 of the U. From Figure 1 it will be seen that the pre-wound field-coils may be readily threaded over said legs of the semi-annular core-portions. The coils 49-52 surround necks 56 of the core, said necks joining the cleft pole parts to the legs 59. Said pole parts are joined by necks 57 forming the middle portions of the semi-annular core-portions. The clefts 58 of the poles may be of such shape that a coil may be placed around the salient body of any one of the pole parts 53-53^a or 54-54^a, as indicated by the dotted line 60 (Figure 1), said dotted line representing a field-coil in such position. Thus one coil 65 may be placed around the neck 56 and an-

other coil around the salient pole part to compensate for field distortion, and thereby conduct to uniform flux density across the pole faces in alternating current operation. The auxiliary coils 66-73 surround the legs 59 of the annulus. Figure 2 shows another form of annulus, in which the coils are all placed around the salient cleft pole parts,—no coil-receiving necks as 56 of Figure 1 being provided.

The annulus is divided into only two portions so that only two joints need be made, a minimum for the number of joints to be made conducting to a good magnetic circuit. Dividing and joining the core at a plane through the core-axis makes possible the use of uniform laminations or punchings. The laminations of the opposite core-portions may overlap at the joints 62, such overlapping being effected, while still providing for uniformity of the punchings, by having the end of one leg of each U-shaped punching extend beyond the plane at which the core-halves are nominally joined while the extent of the other leg falls correspondingly short of said plane. Thus, by reversing the punchings, a short leg abuts a long leg in each pair of punchings which form the completed annular lamination. The aforesaid overlapping of the opposite core-laminations is then effected by reversing alternate pairs or groups of pairs of laminations.

The shapes of the ends of the legs may be made so as to effect interlocking of the pairs of laminations transversely of the motor-axis. The shape of the end of one leg of each punching is therefore preferably in the form of a V or taper 62^a, while the shape of the other leg-end is that of a V-recess or socket 62^b.

Inasmuch as the joints of the magnet-core-portions are surrounded by coils 66, 73, it is unfeasible to fasten the two built-up core-portions together by means of bolts through the overlapping portions of the laminæ. The motor-casing 46 is therefore resorted to as a means for holding the two core-portions together. By making said casing a tight sleeve fitting over the annulus, as indicated at 63, the portions of said annulus are forced together from diametrically opposite directions so that they are rigidly held and cause the end-surfaces of the opposite leg-members 59 to firmly abut and thereby form two good magnetic bonds. Interlocking means between the annulus and casing may be provided to insure against their relative rotation. Keepers 75, which complete a magnetic circuit for coils 66, 73, may function as the last-mentioned means, said keepers passing through slots 77 formed in said casing 46.

It will be understood that the simple sleeve herein shown may be elaborated within the scope of the invention, as, for example, by

splitting said sleeve to permit its expansion and contraction for facilitating insertion of the core and for positive clamping of the same.

5 Variations may be resorted to within the scope of the invention, and portions of the improvements may be used without others.

Having thus described my invention, I claim:

10 1. In an electric motor including a series of pre-wound field-coils, the combination of substantially semi-annular or U-shaped half-cores, the leg-members of each thereof abutting the leg-members of the other, said leg-

15 members surrounded by said pre-wound coils, and means to fasten said half-cores rigidly together in said abutting relation to form two satisfactory magnetic bonds, one at each of the abutments, said fastening means includ-

20 ing a fastening sleeve fitted around said half-cores and forcing them together in diametrically opposite directions to form a complete built-up annular laminated magnetic core, each half-core being formed of U-shaped laminations, each of which is integral, said legs surrounding the armature of the motor.

25 2. In an electric motor including a series of pre-wound field-coils, the combination of substantially semi-annular or U-shaped half-

30 cores, the leg-members of each thereof abutting the leg-members of the other, said leg-members surrounded by said pre-wound coils, and means to fasten said half-cores rigidly together in said abutting relation to form two

35 satisfactory magnetic bonds, one at each of the abutments, said fastening means includ- ing a fastening sleeve fitted around said half-cores and forcing them together in diametrically opposite directions to form a complete

40 built-up annular laminated magnetic core, each half-core being formed of U-shaped laminations, each of which is integral, said legs surrounding the armature of the motor, the four legs of said half-cores being formed

45 to interlock end to end.

3. In an electric motor including a series of pre-wound field-coils, the combination of substantially semi-annular or U-shaped half-cores, the leg-members of each thereof abut-

50 ting the leg-members of the other, said leg-members surrounded by said pre-wound coils, and means to fasten said half-cores rigidly together in said abutting relation to form two satisfactory magnetic bonds, one

55 at each of the abutments, said fastening means including a fastening sleeve fitted around said half-cores and forcing them together in diametrically opposite directions to form a complete built-up annular lami-

60 nated magnetic core, each half-core being formed of U-shaped laminations, each of which is integral, said legs surrounding the armature of the motor, the legs of each of said half-laminations being formed with co-

65 operative tapering and socket ends to effect

interlocking of each half-lamination with its mate.

4. In an electric motor including a series of pre-wound field-coils, the combination of substantially semi-annular or U-shaped half-

70

cores, the leg-members of each thereof abutting the leg-members of the other, said leg-members surrounded by said pre-wound coils, and means to fasten said half-cores rigidly together in said abutting relation to form two

75

satisfactory magnetic bonds, one at each of the abutments, said fastening means includ- ing a fastening sleeve fitted around said half-

80

cores and forcing them together in diametrically opposite directions to form a complete built-up annular laminated magnetic core, each half-core being formed of U-shaped laminations, each of which is integral, said legs surrounding the armature of the motor,

85

the legs of each of said half-laminations be- ing formed with co-operative tapering and socket ends to effect interlocking of each half-

90

lamination with its mate, each half-lamina- tion having one leg formed with a tapered point, and the other leg with a socket point to match, whereby both of said half-cores are built up of duplicate laminations through- out, the laminations in one half-core being reversed relatively to those in the other half-

95

core, so that the points of each half-core are set into the sockets of the other half-core.

95

5. In an electric motor including a series of pre-wound field-coils, the combination of substantially semi-annular or U-shaped half-

100

cores, the leg-members of each thereof abutting the leg-members of the other, said leg-members surrounded by said pre-wound coils, and means to fasten said half-cores rigidly together in said abutting relation to form two

105

satisfactory magnetic bonds, one at each of the abutments, said fastening means includ- ing a fastening sleeve fitted around said half-

110

cores and forcing them together in diametrically opposite directions to form a complete build-up annular laminated magnetic core, each half-core being formed of U-shaped

115

laminations, each of which is integral, said legs surrounding the armature of the motor, the legs of each of said half-laminations be- ing formed with cooperative tapering and socket ends to effect interlocking of each half-

120

lamination with its mate, each half-lamina- tion having one leg formed with a tapered point, and the other leg with a socket point to match, whereby both of said half-cores are built up of duplicate laminations throughout, the laminations in one half-core being re-

125

versed relatively to those in the other half- core, so that the points of each half-core are set into the sockets of the other half-core, the laminations of each half-core being alternate- ly reversed to effect overlapping joints throughout the magnet.

130

6. In an electric motor, a field-structure in- cluding an annular, laminated core consist-

- ing of semi-annular or U-shaped half-portions joined at substantially a plane through the axis of said core, the joints being formed by means of corresponding taper and socket formations at the ends of the several laminations, each half-portion having a cleft pole, each part of said cleft pole being joined to one leg of the U by a coil-receiving neck or loop onto which a pre-wound coil may be slipped by threading it over said leg, each part of the cleft pole being so formed that the salient body thereof formed between the cleft and the aforesaid loop may also receive a pre-wound coil, and core-retaining means whereby said half-portions are embraced and pressure is applied at said joints to form a satisfactory magnetic bond, said pressure being substantially perpendicular to the aforesaid plane at which the core-portions are joined.
7. An annular field-magnet core built up solely of alternately reversed duplicate semi-annular or U-shaped laminations, said laminations forming built-up U-shaped half-cores, which may be separated from each other to thread pre-wound coils over the legs thereof, said half-cores being joined to form the complete annulus, in which the leg-ends of one-half portion abut the leg-ends of the opposite half-portion, at their edges, means for maintaining the edges of the laminations together under pressure by applying a force perpendicularly to the plane of separation between the half-cores, each annular lamination consisting of duplicate abutting U-shaped parts, the legs of the U-shaped laminations having their abutting tips formed with protruding extensions and corresponding recesses, said extensions and recesses matching and interlocking by reason of the reversing of the U-shaped laminations one in respect to the other.
8. Field-magnet as set forth in claim 7, in which alternate annular laminations are also bodily reversed, so that the leg-extensions of adjacent annular laminations overlap and form a satisfactory magnetic bond.

ALFRED E. OSWALD.
